DISPLAY CARTON

Harry Stewart Jones, London, Ontario, Canada

Application June 11, 1934, Serial No. 730,125
In Canada March 28, 1934

1 Claim. (Cl. 206—44)

My invention relates to display paper or cardboard boxes or packages of the type wherein, on opening the flaps of the package, the goods remain in the box and are exhibited through an opening in the top of the box.

The objects of my invention are:

First, to provide a box or package wherein the goods are inserted by the sides of the box, the said sides being held in a closed manner by the 10 folding of the flaps thereof.

Second, to provide a box or package wherein the goods may not be removed without opening the main cover or covers enclosing the same.

Third, to provide a box or package which may be stamped in one piece, easily folded and assembled and comparatively low in cost.

Other objects as well as many advantages of this invention will become apparent in the following description, supplemented by a drawing, 20 in which:

Fig. 1 is a perspective view of the box with the flaps or covers partly open;

Fig. 2 is an end view thereof;

Fig. 3 is a sectional view of the box, provided 25 with one main flap; and

Fig. 4 is a plan view of the paper or cardboard stamping therefor.

The box is constructed of a flat piece of paper or cardboard, comprising a box top 5, in which a 30 window 6 is stamped out, although this window need not necessarily be, but when so provided may be closed with transparent materials in order to exhibit the goods contained in the box and yet prevent any damage done thereto, which may be 35 caused by dust, fingermarks, or atmospheric conditions.

Integral with the top are sides 7 and ends 8, hereinafter called sides and ends, respectively. One side of one of the ends of end 8 is integral 40 with the bottom of the box 9, and the other side of such end 8 is integral with a lip 10, adapted to be glued or fastened to bottom 9 when the box is folded together, as shown in Figs. 1 and 3. Sides 7 each comprise an extension 11 forming 45 the upright walls of the box and a tongue 12, adapted to fold and lie flat in the box underneath the goods. The bottom 9 of the carton is also provided with extensions which merge into oppositely extending flaps 14. The extensions 13 50 are so disposed as to provide outer side walls corresponding to the inner side walls formed by the extensions 11 and also so that the integral flaps 14 may fold over the box, as shown in Fig. 2.

As previously stated, all sections of this box 55 comprise one unit, the different parts being de-

fined by creases indicated by double lines. In making up the box or package, the stamping is folded on two creased lines joining the cover 5 and the bottom 9, so that the bottom lies underneath the top, and similarly the stamping is 5 folded at 90 degrees on the creases of end 8, lip 10 being glued or fastened in some way to the bottom. The goods may then be inserted by the openings provided at the two open sides which may then be closed by folding on the creases between the top of the tongues 12, so that the same will lie as shown at 15 in Fig. 3, after which they may be opened in the manner shown at 16 in the same figure. The box is then completely closed by folding flaps 14 on the creases on each side 15 of extension 13, until they lie in the position shown in Fig. 2, forming a completely enclosed rigid package affording complete protection to the goods it contains.

If desired, one of the sides may have its 20 tongue glued or otherwise fastened to the bottom of the package permitting entry of the goods by the other side only. Similarly, it may be said that only one flap 14 may be employed, if desired, as shown in Fig. 3. When two flaps are 25 used, each may either overlap fully, as shown in Fig. 2 or may cover substantially one half of the top of the package. It is to be understood that, if desired, some means may be provided for fastening the flaps together. 30

What I claim is:

A foldable blank for producing a display carton comprising a one-piece body including a centrally apertured rectangular part formed with two spaced pair of spaced transversely extending parallel scores dividing said part into a top forming portion, a pair of side wall forming portions hinged to and for folding downwardly from opposite sides of said top and a pair of tongue forming portions hinged to and for folding inwardly from the bottoms of said walls, an end wall forming part hinged at one side to and folding downwardly from one end of said top, an oblong part hinged at one side to the other end of said top, formed at its longitudinal median with a score dividing it into the other end wall forming portion for folding downwardly from the other end of said top and a lip forming portion for folding inwardly from the bottom of said other side wall, and a rectangular part of greater length than and disposed in parallel spaced relation to said other rectangular part, said elongated rectangular part being hinged centrally of one side thereof to the other side of the said end wall forming part and formed with two 45

50

55

spaced parallel pair of spaced transversely extending parallel scores dividing it into a bottom forming for folding against the lower face of said tongues and the upper face of said lip and
5 adapted to be anchored to the lip, a pair of extension forming portions hinged at one side to the sides of and for folding upwardly from said

bottom against the said side walls and a pair of oppositely disposed flap forming portions hinged to the other side of and for folding inwardly from said extensions in overlapping relation with respect to the outer face of said top. 5

HARRY STEWART JONES.
